CLAIM

The ornamental design for a Kaiser roll cutter mold, as shown and described.

DESCRIPTION

FIG. 1 is a top view of a Kaiser roll cutter mold according to the invention shown incorporated into a dough forming and cutting roller assembly which is illustrated in phantom;

FIG. 2 is a front elevational view of the Kaiser roll cutter mold of the invention, with the rear elevational view being a mirror image thereof;

FIG. 3 is a right side view of the Kaiser roll cutter mold of the invention, with the left side view being a mirror image thereof;

FIG. 4 is a top view of the Kaiser roll cutter mold of the invention; and,

FIG. 5 is a bottom view of the Kaiser roller cutter mold.

The broken lines in FIG. 1 showing multiple cutter molds on a drum supported by an arm and rotatably mounted, along with a roller, on a shaft, as well as the broken lines in each of FIGS. 1, 4 and 5 showing apertures in the cutter mold(s), are for illustrative purposes only and form no part of the claimed invention.
